CLAIM

The ornamental design for a dish drying rack, substantially as shown and described.

DESCRIPTION

FIG. 1 is a perspective view of a dish drying rack in an extended position, showing our new design;
FIG. 2 is a top plan view thereof;
FIG. 3 is a front elevational view thereof;
FIG. 4 is a left side elevational view thereof;
FIG. 5 is a rear elevational view thereof;
FIG. 6 is a bottom plan view thereof; and
FIG. 7 is a perspective view thereof in a retracted position.
